UNITED STATES PATENT OFFICE.

LAMBERT BROUHON, OF AIX-LA-CHAPELLE, GERMANY, ASSIGNOR OF ONE-HALF TO JEAN BINDELLE, OF SAME PLACE.

FURNACE.

SPECIFICATION forming part of Letters Patent No. 669,978, dated March 19, 1901.

Application filed August 3, 1900. Serial No. 25,800. (No model.)

To all whom it may concern:

Be it known that I, LAMBERT BROUHON, engineer, a citizen of Germany, residing at 1 Lütticherstrasse, Aix-la-Chapelle, Kingdom 5 of Prussia, Germany, have invented certain new and useful Improvements in Furnaces; and I do hereby declare the following to be a full, clear, and exact description of the invention, such as will enable others skilled in 10 the art to which it appertains to make and use the same.

My present invention consists in an improved construction of a furnace and arrangement of its parts so that it can be used in any 15 kind of boiler plants; and the object in view is saving of fuel and consuming of smoke.

In the accompanying drawings, Figure 1 is a front view of my invention attached to a head of a boiler. Fig. 2 is a horizontal section of my invention, a part of the flue not shown in section; and Fig. 3 is a top plan view.

The novelty of my invention consists in providing the combustion-chamber attachment *a* with one or more back-draft flues *b*, 25 connected by means of secondary channels *c* with the smoke-stack (not shown) in the shortest way possible.

By means of this arrangement the velocity 30 of the gases, which in the ordinary way escape beyond the fire-grate *d*, is checked, and the flames cannot escape toward the smoke-stack in an inclined position, as hitherto, but are compelled to remain for a longer space of 35 time in a vertical position over the grate, so that the suspended particles of coal find time to fall back upon the fire, and the otherwise uselessly carried off carbonic acids are completely burned at the existing perfect white heat.

40 The area of the flue or flues *b* does not need to exceed the area of the fire-door *e*, but must be smaller than the area of the main flue just beyond the fire-grate *d*. The draft in the flue *b* can be suitably regulated by means of a 45 damper *f*, which must be set to suit each individual case.

In operation the damper *f*, suitably mounted on the rod *g* in flue *b*, is turned by means of the lever *h*, also mounted on the rod *g*, and 50 chains *i* and *k*. The chain *i* is fastened to a disk *l* on the bar *m*, forming the pivot of the door *e*, which shows a well-known construc-

tion, while chain *k* runs over a sheave *n*, mounted in a bracket *o* on flue *b*, and carries the weight *p*. Now it is clear that when the door 55 *e* is opened the damper *f* takes up a position, as shown in Fig. 3, giving to the flue *b* the largest possible area, and the cold air, entering through the door *e* while fuel is thrown in will of necessity be drawn off through the 60 flue *b* without coming into contact with the fire upon the grate nor have a chance to cool off the walls of the combustion-chamber proper.

Under the door *e*, Fig. 1, and under the 65 grate the door *q* is pivotally attached to give admittance to the ash-pit. Within the attachment *a* there is a shell *r*, with openings corresponding with the doors *e* and *q* and one to correspond with the flue *b*. Between said 70 upper door *e* and ash-pit door *q* said shell *r* is provided with a horizontal division-plate *s* to separate the combustion-chamber from the ash-pit. By this means the temperature in the main flue and in the smoke-stack is 75 lowered considerably and the draft checked just at the time when excessive smoke is forming, so that the fine particles of coal-dust remain in the combustion-chamber and have a 80 chance of getting burned. As soon as the door 85 *e* is closed the temperature in the main flue and smoke-stack rises again, and the combustion is gradually carried on in the above-mentioned manner until a new supply of fuel demands the opening of the fire-door once more. In this manner the draft is automatically regulated throughout the working of the plant.

I claim—

1. In a smoke-consuming furnace, a combustion-chamber attachment *a* provided with a flue *b* to lead off the cold air when fuel is thrown in, a damper *f* in said flue giving the maximum area of the flue free when the door *e* is opened and diminishing said area when 95 said door is shut, a lever *h* fastened to the prolonged rod *g* of said damper and connected with said door and to a weight *p* by means of chains *i*, *k* and a shell within said attachment with openings to correspond with said doors 100 and with said flue and a horizontal division-plate to separate the combustion-chamber from the ash-pit, substantially as described.
2. In a smoke-consuming furnace, in com-

bination with a combustion-chamber attachment *a*, provided with one or more flues *b* for leading off cold air when the door is open, a damper *f* to control the area of said flue, a lever *h* on the rod *g* of said damper, standing under the control of the door *e* by means of a chain *i* fastened to a disk *l* on bar *m* secured to said door, and under the control of the weight *p* by means of a chain *k* running over

5 a sheave *n* mounted in a bracket *o* on flue *b*,

and a shell within said attachment *a*, substantially as shown and described.

In testimony that I claim the foregoing as my invention I have signed my name in presence of two subscribing witnesses.

LAMBERT BROUHON.
